United States Patent

Des. 237,391
Patented Oct. 28, 1975

237,391

ANIMAL EXERCISER

Allan H. Willinger, New Rochelle, Albert J. Dinnerstein,
Brooklyn, and Jacques Le Baigue, Westbury, N.Y.,
assignors to Metaframe Corporation

Filed Sept. 25, 1972, Ser. No. 292,257

Term of patent 14 years

Int. Cl. D30—07

U.S. Cl. D30—42

FIG. 1.

FIG. 2.

FIG. 3.

FIG. 4.

FIG. 5.

FIG. 6.

FIG. 7.

FIG. 1 is a front elevational view of an animal exerciser showing our new design;

FIG. 2 is a rear elevational view thereof;

FIG. 3 is a right side elevational view;

FIG. 4 is a left side elevational view;

FIG. 5 is a top plan view thereof;

FIG. 6 is a bottom plan view thereof; and

FIG. 7 is a perspective view thereof.

We claim:

The ornamental design for an animal exerciser, substantially as shown.
